UNITED STATES PATENT OFFICE.

BENJAMIN ROBERT ROLPH, OF WINNIPEG, MANITOBA, CANADA.

OIL-BURNER.

1,087,141

Specification of Letters Patent.

Patented Feb. 17, 1914.

Application filed December 12, 1912. Serial No. 736,325.

To all whom it may concern:

Be it known that I, BENJAMIN ROBERT ROLPH, of the city of Winnipeg, in the Province of Manitoba, Canada, have invented certain new and useful Improvements in Oil-Burners, of which the following is the specification.

The invention relates to an improvement in oil burners and the object of the invention is to provide a convenient and economical means for utilizing the thermal energy of common oil or other fluid hydrocarbons.

The invention consists essentially in the arrangement and construction of parts hereinafter more particularly described and later pointed out in the appended claims.

Figure 1 represents a longitudinal sectional view through the device parts being shown in side elevation. Fig. 2 represents a vertical cross sectional view through the same, the section being taken in the plane denoted by the line X—X' Fig. 1 and looking in the direction indicated by the arrow "a".

Fig. 3 represents a vertical sectional view through the device, the section being taken in the plane denoted by the line Y—Y' Fig. 1 and looking in the direction indicated by the arrow "b". Fig. 4 represents an enlarged detailed horizontal sectional view through the needle valve seat and adjoining parts, part of the valve being shown in side elevation.

In the drawing like characters of reference indicate corresponding parts in each figure.

1 represents a tubular member having the ends thereof closed by caps 2 and 3 and divided centrally by a cross piece 4 thereby providing a vaporizing chamber 5 and a superheating chamber 6 at opposite sides of the partition 4.

7 is a tube passing through the cap 3 into the tubular member 1 which tube passes more or less centrally through the partition 4 and terminates in a closed end a short distance away from the cap 2. This tube is connected with a suitable oil supply controlled by a stop cock 8 inserted in the tube.

The end of the tube within the vaporizing chamber is provided on the top side with a series of small holes 9 to admit the oil to the vaporizer when in use. A packing of asbestos, mineral wool, pumice stone or other such like non-combustible material 10 is placed within the vaporizing chamber and beneath and to the sides of the tube, care be-

ing taken that the holes 9 are not closed or covered over.

The cross piece 4 is provided with a port 11 which connects the vaporizing chamber 5 with the superheating chamber.

12 is a pan supplied with a similar upwardly directed pair of brackets, 13 and 14, which brackets are looped around the tubular member 1 to support the same above the pan.

15 represents a burner located beneath the tubular member 1 and supported in any suitable manner by the brackets. The burner has a series of openings 16 located in the upper side thereof and has one end permanently closed by a cap 17, the opposite end being fitted with a contracted coupling pipe 18 which receives the inner end of an extending pipe 19 fitted with a series of air inlet openings 20 and carrying an adjustable sleeve 21, the sleeve being arranged to close when desired the openings thereby permitting of a variation of the amount of air fed into the pipe through the openings.

22 is a valve casing carried by the forward end of the pipe 19 into which it opens. The casing is fitted with a valve seat 23 and an orifice 24 and carries a stuffing box 25 fitted with a valve 26 having the stem 27 thereof threaded into the box for adjusting purposes. The outer end of the stem is supplied with a hand piece 28 and the inner end is contracted at 29 to form a shoulder 30, designed to close on the valve seat 23, the contracted portion of the stem being designed to pass into and through the orifice 24 for cleaning purposes.

31 is a pipe having the forward end opening to the interior of the valve casing and the rear end thereof passing through the cap 3 into the interior of the superheating chamber.

32 is a drip pipe passing from the pipe 7 downwardly toward the pan. This pipe is supplied with a stop cock 33.

In the operation of the device a small quantity of oil is allowed to run into the pan through the pipe 32, this being accomplished by turning the stop cock 33. When sufficient oil is in the pan said stop cock is closed and the oil is admitted to the vaporizing chamber by opening the stop cock 8, it being understood that the oil is passed through the openings 9 and absorbed by the packing. The oil in the pan is ignited and the flames quickly heat the vaporizer and the

- packing so that the oil contained therein is vaporized and passed to the superheater through the port 11. From the superheater the vaporized oil enters the pipe 31 and 5 passes to the burner, the amount being regulated by the valve. In passing through the superheater the vaporized oil is heated to a high temperature and converted into a gas, it being noticed that the superheater is located in the zone of the flame arising from the pan. Prior to entering the burner the gas is mixed with air passed through the openings 20, the supply of this air being readily controlled by the attendant through the manipulation of the sleeve 21. By the time the oil in the pan is exhausted the gas is flowing freely through the openings 16 in the burner where it amply serves to keep the vaporizer and superheater up to the required 15 temperature.
- The contracted end of the valve serves the important function of cleaning out the orifice 24 each time the valve is closed. If no such provision were made the orifice would become quickly clogged with carbon particles after the burner had been in use for a short time. This would greatly depreciate the use 25 of the device.
- The burner is particularly adapted for placing in the ordinary stove to convert it into an oil stove or to be used in connection with water heaters or boilers. Many other uses can readily be found for it however embodying the essential features of the invention.
- What I claim as my invention is:—
1. In an oil burner, the combination with a burner and a vaporizing chamber, of a superheating chamber adjoining the vaporizing chamber and opening to the same, an oil feed pipe passing through the superheating chamber and into the vaporizing chamber, said pipe having the portion entering the vaporizing chamber fitted with a series 40 of openings, a packing within the vaporizing chamber and adjoining the pipe and means connecting the superheating chamber with the burner, as and for the purpose specified.
  2. In an oil burner, the combination with a burner and a vaporizing chamber, of a superheating chamber adjoining the vaporizing chamber and opening to the same, a feed pipe passing through the superheating chamber and entering the vaporizing chamber, said pipe having the portion thereof entering the latter chamber provided with a series of openings, a packing within the vaporizing chamber and adjoining the pipe, a pipe leading from the superheating chamber and communicating with the burner, means for controlling the passage of the vaporized oil through the latter pipe and adjustable means for mixing air with the vaporized oil prior to admitting the same to the burner, as and for the purpose specified.
  3. In an oil burner the combination with a burner and a vaporizing chamber, of a superheating chamber adjoining the vaporizing chamber and opening to the same, a feed pipe passing through the superheating chamber and entering the vaporizing chamber, said pipe having the portion thereof entering the latter chamber provided with a series of openings, a packing within the vaporizing chamber and adjoining the pipe, a pipe leading from the superheating chamber, a pipe extending from the burner and provided with a number of openings, an adjustable sleeve on the latter pipe, a valve 75 casing connecting the ends of the latter pipes, said casing presenting a valve seat, and a valve operating on the seat, as and for the purpose specified.

Signed at Winnipeg this 14th day of March, 1913.

BENJAMIN ROBERT ROLPH.

In the presence of—

G. S. ROXBURGH,
L. GOULD.
